PAPER MAKING MACHINE

Samuel Amantea, Niagara Falls, N. Y.

Application November 12, 1934, Serial No. 752,643

15 Claims. (Cl. 92—44)

It is well known to those skilled in the art that in paper making machines of the Fourdrinier type, the woven wire screen or endless apron must frequently be replaced. In present practice, when such repairs are to be made, practically all of the wet end of the machine must be dismantled, requiring the removal of the endless deckles, supports, rolls, suction boxes, trays, apron boards, etc., and the subsequent replacement thereof.

It has been the principal object of my invention to provide means whereby the wire screen or endless apron of a Fourdrinier machine may be easily and quickly removed from the machine without the usual expenditure of time and labor in dismantling parts thereof.

Another object has been to do away with the customary endless deckle straps and to provide in their places deckles which may be easily and quickly removed when it is necessary to change the apron.

A further object is to provide a slice member having an edge which may be adjusted to a fine degree of accuracy.

Moreover, my invention contemplates the use of an outlet box movably connected to the head box of a paper making machine and provided with means whereby it can be quickly moved out of the way without having to be disassembled or removed from the machine.

Furthermore, my invention is so designed that the changing of the woven wire screen or endless apron of a Fourdrinier machine may be made with the expenditure of very little time and labor.

Moreover, in my invention, the apron extending to the breast roll is carried by the outlet box.

The above objects and advantages have been accomplished by the device shown in the accompanying drawings, of which:

Fig. 1 is a side elevation, partly in section, of my improved device.

Fig. 2 is a front elevation thereof, partly in section, with portions broken out.

Fig. 3 is a plan view of the device, partly in section, and with portions thereof being broken out.

Fig. 4 is an enlarged, fragmentary, sectional view and is taken on line 4—4 of Fig. 3.

Fig. 5 is an enlarged, fragmentary view of the interior of the outlet box with the slice removed and is taken on line 5—5 of Fig. 3.

Fig. 6 is an enlarged, fragmentary, sectional, plan view showing one side of the outlet box with its associated parts and is taken on line 6—6 of Fig. 4.

Fig. 7 is an enlarged, sectional view taken on line 7—7 of Fig. 4.

Fig. 8 is a side elevation of a modified form of structure.

Fig. 9 is a sectional elevation of the same and is taken on line 9—9 of Fig. 8.

Referring to the form of invention shown in Figs. 1 to 7, inclusive, my invention is to be applied to the head box 10 of the ordinary Fourdrinier machine, and comprises, in general, an outlet box 11 mounted upon a platform 12 and arranged in telescoped relation with the head box 10 of the machine. This outlet box carries the slice 13 and the deckles 14. For convenience of illustration, I have shown only the breast roll 15, the table or frame 17 of a Fourdrinier machine, and a number of table rolls 16, together with a portion of the wire screen 18.

The outlet box 11 comprises two side walls 20 and 21 which have their outer faces in engagement with the inner faces, respectively, of the side walls 22 and 23 of the head box. The outlet box is also provided with a bottom 24 which is, of course, secured to the side walls 20 and 21 and which is supported on suitable tracks 25 carried by the supporting platform 12. The platform is, of course, arranged immediately in front of the breast roll 15 and the parts are so designed that the bottom 24 extends forwardly to a point near the vertical center line of the breast roll, as shown in Fig. 4, when the outlet box is in its working position. Extending across the rear edge of the bottom 24 of the outlet box, is an angle iron 26, the vertical leg 27 thereof being preferably flush with the inside edge of the bottom. The horizontal leg 28 is preferably of the same thickness as the tracks 25, and a packing strip 29 is carried by the platform 12 and engages with the legs 27 and 28 of the angle iron 26, whereby the joint across the bottom of the outlet box is sealed.

A shaft 43 is suitably carried by the walls 22 and 23 of the head box 10 and in such position as to be located some distance above the walls 20 and 21 of the outlet box. This shaft is provided with a hand wheel 44 whereby it may be rotated. Also carried by the shaft 43 are two gear pinions 51 which are arranged over the walls 20 and 21 of the outlet box and which are engageable with gear racks 58 carried by these walls. A bolt 59 is designed to be passed through adjacent walls 20 and 22, and 21 and 23, respectively, of the outlet box and the head box to draw the two engaging wall surfaces together when the

outlet box is in its normal position, and thus prevent leakage between such side walls.

As shown in Figs. 3 to 6, inclusive, the forward edge of the bottom of the outlet box is provided with a recess 30 in which is disposed the rear edge 5 of a flexible apron 31. This apron extends forwardly to a point substantially over the vertical center line of the breast roll 15. The recess 30 extends clear across the forward edge of the bottom 10 and is of a depth equal to substantially one-half the thickness of the bottom. Arranged on top of the apron 31 and within the recess is an apron retaining plate 32 which is held in place by a plurality of screws 33 having their heads 34 15 counter sunk flush with the top of the retaining plate. The retaining plate is of such thickness that when in place, it is level with the top surface of the bottom 24 of the box. The side walls 20 and 21 of the box are so shaped that the lower edge surface 35 of each extends forwardly beyond the forward edge of the bottom 24 a distance 20 slightly beyond the vertical center line of the breast roll 15. Such surface is preferably in the same plane as the top surface of the bottom 24. 25 The recess 30 cut in the forward edge of the bottom extends clear across the bottom and under the side walls 20 and 21, whereby the flexible apron 31 may be passed under the surfaces 35 of the side walls and up on the outside surfaces 30 thereof, as shown in the drawings and particularly in Fig. 7. The apron is made of such length that its ends 36 can be brought up on the outside of the surfaces of the walls a considerable distance. These ends are secured in place preferably by means of a clamp plate 37, carried by each 35 side wall of the outlet box and retained in place by means of cap screws 38 which pass through the plates and the ends 36 of the apron and are screwthreaded into the side walls. Due to the 40 fact that the recess 30 is formed under the side walls 20 and 21, the retaining plate 32 also extends under these side walls and on top of the apron.

The side walls 20 and 21 are each provided 45 with an overhanging portion 42 which is bounded by vertical surfaces 39 and 40 connected by an inclined surface 41. The lower end of each of the surfaces 40 meets and joins the forward end 50 of each of the surfaces 35. A vertical groove 45 is formed in the inner face of each of the side walls 20 and 21 and located preferably a short 55 distance behind the surface 40 of the wall for the reception of the vertical edges of the slice 13. Each of these grooves extends down to within a short distance from the surface 35 of the wall, as clearly shown in Fig. 5, whereby ledges 46 are 60 provided which act as stops in the event that the adjusting screws should allow the slice to move downwardly beyond its adjusted position. Carried on the inner face of each of the side walls is a vertically arranged guide member 47. This 65 guide member is preferably angular in cross-section and one of its legs 48 is secured to the side wall. The other leg 49 of the member extends inwardly toward the center of the outlet box and is so positioned that its face will be coincident with the front face of the groove 45. A groove 50 is formed in the leg 49 of this member, and a ridge 51, formed near the vertical edge 70 at each side of the slice, is designed to engage with and be guided by this groove.

The overhanging portions 42 of the side walls 20 and 21 are preferably connected together by 75 means of a spacing bar 52. This bar is for the

purpose of stiffening the structure and supporting the slice 13 at one point or a number of points throughout its length, and may carry one or more rings 53 held in place by screws 54 and carrying an adjustable screw or bolt 55, the head of which is brought to bear against the outer surface of the slice 13. When the bolt 55 has been adjusted so as to place the proper pressure upon the slice, it is set in such adjusted position by means of a lock nut 56 carried thereon. For clearness of 10 illustration, I have shown but one ring 53 arranged at the center of the slice, but obviously, any number may be employed, depending upon the amount of support required by the slice.

The slice 13 has an angle iron member 60 secured along its upper edge and, carried at each end of this member, is an arm 61 which projects above the member and out beyond the end thereof. Each of these arms carry an adjusting screw 62 having a lock nut 63. Each adjusting screw 20 extends downwardly and engages an angle iron member 64, carried by each of the side walls 20 and 21 of the outlet box and arranged on the outer surfaces thereof. By means of these screws, the vertical position of the slice 13 may be 25 adjusted.

The slice 13 of my invention does not extend down to the wire screen 18, but it is provided at its lower end with an adjustable slice member 65. This member is preferably made of some flexible material, such as rubber, and it is disposed on the inside surface of the slice 13 and is held in place by a number of bolts 66. These bolts pass through slots 67 formed in the lower portion of the slice 13, whereby the member may be vertically adjusted. Each of the bolts extends through the center of the slots 67 of the slice and through the head 68 of an adjusting rod 69. These adjusting rods extend upwardly to the top of the slice, being provided with an offset portion 70 which carries them to the front side of a stiffening flange 71, secured to the slice and extending substantially the full length thereof. The upper end of each of the adjusting rods is screwthreaded and passes through a suitable aperture formed in 45 the horizontal flange of the member 60 at the upper edge of the slice. Each bolt is provided with an adjusting nut 72 at each side of this flange, whereby the rod may be raised and lowered. Throughout the length of the slice and the slice 50 member there are provided a number of these adjusting rods, whereby the working face of the slice member 65 may be adjusted throughout its length to a fine degree of accuracy. If desired, the rubber or other flexible material forming the 55 adjustable slice member 65 may be formed with a number of embedded pieces of flexible material 73 for stiffening the same. These embedded pieces of material are preferably so located that the slice bolts 66 pass centrally therethrough, whereby the 60 slice member will not only be stiffened, but the adjusting movement of the rods 69 will be more evenly distributed across the working edge of the member.

A deckle 75 is provided at each side of my outlet 65 box and comprises an angle iron 76 and a piece of flexible material, such as rubber, in the form of a strip 81 which is secured to the vertical leg 77 of the angle by means of a number of bolts 78 which pass through the vertical leg and the 70 clamping bar 79. The inner ends of the deckle angles are secured to the outside face of each of the side walls 20 and 21 by means of cap screws 80. These screws are passed through the legs 77 of the angles and the upper ends 81 of the apron, 75

and are screw-threaded into the side walls. Since the apron does not extend back to the end of the angle, a filler 82 of the same material and thickness as the apron is placed between the side wall 5 and the inner leg of the angle at a point where the rear cap screw 80 is located. A wedge-shaped filler 83 is provided on the inside of each deckle and, as shown in Fig. 6, extends forwardly from the vertical edge 40 of each of the side walls 20 and 21 and meets and joins the inner face of the flexible strip 81 of the deckle at some point in front of the edge. Each of these wedge-shaped fillers is preferably located between the clamping bar 79 and the flexible strip 81 of the deckle and thus provides smooth surfaces for the passage of the pulp as it moves out from under the slice forwardly on the screen and between the deckles. The rearwardly projecting ends of the angles 75 of the deckles 14 are each preferably provided 20 with slotted holes 84 through which the cap screws 80 pass, whereby the lower working edges of the flexible strips 81 of the deckles may be adjusted to the upper surface of the screen. The bolts 78 which hold the flexible strips 81 in place upon the deckles are passed through vertically arranged slots 85 formed in the leg 77 of the angle 76, whereby the clamping plates 79 and the flexible strips 81 may be suitably adjusted. Each of the deckles is supported in its working position 30 preferably by means of a brace 86, having its lower end secured to the leg 76 of the angle 75 and its upper end secured to the outlet box preferably by being attached to the angle irons 64, carried thereby.

35 In the modified form of invention shown in Figs. 8 and 9, the outlet box 90 is pivotally secured to the platform 91 at suitable points throughout the width of the box. The inner ends of the side walls 93 of the outlet box and the pivotal points 92, therefore, are located some 40 distance back from the forward edges of the walls 94 of the head box 95, whereby the outlet box 90 is in telescopic relation with the head box 95 and may thus be moved from the full line position of Fig. 8 to the dotted line position thereof.

45 In these figures I have also shown suitable means for conveniently elevating the forward end of the outlet box. These means comprise a shaft 96 extending preferably across the full width of the box and mounted in suitable bearings 97 carried by the platform 91. On this shaft is mounted a number of cams 98. These cams are preferably eccentric in form and are so designed that, when in their maximum positions, the outlet box will be moved to the dotted line position of Fig. 8. Each of these cams is 50 preferably provided with a flattened surface 99 for engagement with the outlet box when occupying its maximum position, whereby when in such position, the cams will be held in place by such flattened surfaces and thus be prevented from accidental rotation caused by the weight of the outlet box. Suitable operating means are located at some convenient point on the 55 shaft 96, and, as clearly shown in Figs. 8 and 9, these may comprise a ratchet wheel 100 and an operating arm 101. The operating arm is loosely mounted upon the end of the shaft and is engaged with the ratchet wheel by means of a spring-pressed ratchet pawl 102. A locking 60 ratchet pawl 103 is carried by a bracket 104 secured to the forward edge of one of the side walls 95 of the head box, and serves to retain the ratchet wheel in any position to which it is 65 operated by the operating arm 101.

The platform is provided near its rear end with a suitable packing strip 105, whereby the joint across the bottom of the outlet box will be sealed when the box is in its normal position.

From the foregoing, it will be obvious that when it is desired to replace the wire screen 18 on a Fourdrinier machine to which my invention has been applied, it is only necessary to remove the deckles 14 which can be easily and quickly accomplished by simply removing the two cap 10 screws 80, the bolts 59, and the bolts securing the upper ends of the braces 86 to the outlet box 11. After the deckles are removed, the hand wheel 44 is operated, and, through the medium of the gear pinions 51 and racks 58, the outlet 15 box 11 is drawn into the head box 10. The outlet box may thus be drawn to the dotted line position shown in Fig. 1, where the screen will be accessible for easy and quick removal. When the outlet box is being drawn back into the head 20 box, the same will slide upon the tracks 25 carried by the platform 12. When the screen 18 has been replaced, it is only necessary to operate the hand wheel 44 in the opposite direction to cause the outlet box to be moved forwardly to 25 its operative position or that shown in full lines in Fig. 1, whereupon the deckles 15 may be re-assembled in position.

The angle iron 26 along the rear edge of the bottom 24 of the outlet box will act as a stop 30 as it comes in contact with the rear edge of the platform 12, the packing 29 serving to seal the joint at this point by contact with the angle.

When the deckles are removed, it will be clear 35 that the apron 31 will be held in place because the clamping plates 37 and screws 38 are not disturbed. It will be obvious that when replacing the wire screen, as above described, no adjustments are necessary in replacing the parts and the entire operation may be accomplished in 40 a very short time and with very little labor.

When it is desired to replace the wire screen 18 of the form of invention shown in Figs. 8 and 9, the deckles 15 having been removed, the operating handle 101 is raised and lowered to 45 cause the ratchet wheel 100 to be rotated so as to bring the cams 98 from their inoperative positions, shown in Fig. 9, to their maximum operative positions shown by dotted lines in Fig. 8. Such operation of the cams will cause the forward end of the outlet box 90 to be elevated to the dotted line position. The cams are so proportioned that there will be sufficient clearance between the bottom of the outlet box and the breast roll to enable the workmen to quickly 55 change the wire screen without any interference.

While I have specified rubber as being employed for the apron 31 and for the flexible strips 81 of the deckles 15, it is possible to use canvas or other fabric which has been properly treated to 60 make it waterproof.

Obviously, these and other modifications of the details herein shown and described may be made without departing from the spirit of my invention or the scope of the appended claims, and I do 65 not, therefore, wish to be limited to the exact embodiment herein shown and described, the form shown being merely a preferred embodiment thereof.

Having thus described my invention, what I 70 claim is:

1. A paper making machine, comprising a head box, a movable outlet box in telescoped relation with the head box, and means for moving the outlet box into the head box.

2. A paper making machine, comprising a head box, a movable outlet box in telescoped relation with the head box, deckles carried by said outlet box, and means for moving the outlet box into the head box.
3. A paper making machine, comprising a head box, a movable outlet box in telescoped relation with the head box, a flexible apron carried by the bottom of the outlet box, and means for moving the outlet box into the head box.
4. A paper making machine, comprising a head box, a movable outlet box in telescoped relation with the head box, deckles carried by said outlet box, a flexible apron carried by the bottom of the outlet box, and means for moving the outlet box into the head box.
5. A paper making machine, comprising a head box, a movable outlet box in telescoped relation with the head box, an adjustable slice carried by the outlet box, and means for moving the outlet box into the head box.
6. A paper making machine, comprising a head box, a movable outlet box in telescoped relation with the head box, an adjustable slice carried by the outlet box, a flexible apron carried by the bottom of the outlet box, and means for moving the outlet box into the head box.
7. A paper making machine, comprising a head box, a movable outlet box in telescoped relation with the head box, an adjustable slice carried by the outlet box, deckles carried by said outlet box, a flexible apron carried by the bottom of the outlet box, and means for moving the outlet box into the head box.
8. A paper making machine, comprising a head box, a movable outlet box in telescoped relation with the head box, and rack and pinion means for moving the outlet box into the head box.
9. A paper making machine, comprising a head box, a movable outlet box in telescoped relation with the head box, comprising side walls and a bottom, a flexible apron carried by the forward edge of the bottom, and means for moving the outlet box into the head box.
10. A paper making machine, comprising a head box, a movable outlet box in telescoped relation with the head box, comprising side walls and a bottom, the forward edge of the bottom being formed with a recess, a flexible apron disposed in the recess, an apron retaining plate disposed in the recess and on top of the apron, and means for moving the outlet box into the head box.
11. A paper making machine, comprising a head box, a movable outlet box in telescoped relation with the head box, comprising side walls,
- a slice carried by the outlet box, means for adjusting the slice, a flexible slice member carried by the slice, spaced adjusting means carried by the slice and engageable with the member, and means for moving the outlet box into the head box.
12. A paper making machine, comprising a head box, a movable outlet box in telescoped relation with the head box, comprising side walls, each formed with a vertical groove, a slice carried by the outlet box and having its vertical edges slidably mounted in the grooves, means for adjusting the slice, a flexible slice member carried by the slice, spaced adjusting means carried by the slice and engageable with the member, and means for moving the outlet box into the head box.
13. A paper making machine, comprising a head box, a movable outlet box in telescoped relation with the head box, comprising side walls and a bottom, each of the side walls formed with a vertical groove, a slice carried by the outlet box and having its vertical edges slidably mounted in the grooves, means for adjusting the slice, a flexible slice member carried by the slice, spaced adjusting means carried by the slice and engageable with the member, a flexible apron carried at the forward edge of the bottom, and means for moving the outlet box into the head box.
14. A paper making machine, comprising a head box, a movable outlet box in telescoped relation with the head box, comprising side walls and a bottom, each of the side walls formed with a vertical groove, a slice carried by the outlet box and having its vertical edges slidably mounted in the grooves, means for adjusting the slice, a flexible slice member carried by the slice, spaced adjusting means carried by the slice and engageable with the member, the forward edge of the bottom being formed with a recess, a flexible apron disposed in the recess, an apron retaining plate disposed in the recess and on top of the apron, and means for moving the outlet box into the head box.
15. A paper making machine, comprising a head box, a movable outlet box in telescoped relation with the head box, comprising side walls, a slice carried by the outlet box, means for adjusting the slice, a flexible slice member carried by the slice, metal inserts formed in the slice member, and spaced adjusting means carried by the slice and engageable with the slice and inserts.

SAMUEL AMANTEA. 55
